US00D989902S

(12) United States Design Patent (10) Patent No.: US D989,902 S
(45) Date of Patent: * Jun. 20, 2023

(54) INFLATABLE SPRINKLER POOL

(71) Applicant: ANBEL PLASTIC
MANUFACTURING LTD, Zhongshan
(CN)

(72) Inventor: Wu He, Zhongshan (CN)

() Term: 15 Years

(21) Appl. No.: 29/769,381

(22) Filed: Feb. 4, 2021

(30) Foreign Application Priority Data

Oct. 13, 2020 (CN) 202030608494.8

(51) LOC (14) Cl. 21-03

(52) U.S. Cl.

USPC D21/815

(58) Field of Classification Search

USPC D21/811, 815, 801, 803, 804, 805, 809,
D21/816; D25/2; D6/604

CPC E04H 4/00; E04H 4/0025; E04H 4/0018;
E04H 4/0031; E04H 4/0037

See application file for complete search history.

(57) CLAIM

The ornamental design for an inflatable sprinkler pool, as shown and described.

DESCRIPTION

FIG. 1 is a perspective view of an inflatable sprinkler pool showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1; and,

FIG. 10 is an enlarged view of portion 10 shown in FIG. 3.

1 Claim, 10 Drawing Sheets
